UNITED STATES PATENT OFFICE.

EDWARD R. IVES, OF BRIDGEPORT, CONNECTICUT, ASSIGNOR TO IVES,
BLAKESLEE & CO., OF SAME PLACE.

TOY PISTOL.

SPECIFICATION forming part of Letters Patent No. 242,415, dated May 31, 1881.

Application filed February 2, 1881. (No model.)

To all whom it may concern:

Be it known that I, EDWARD R. IVES, of Bridgeport, in the county of Fairfield and State of Connecticut, have invented a certain new and useful Improvement in Toy Pistols or Fire-Arms, of which the following is a specification.

The object of this invention is to provide a toy fire-arm in which the danger of accidentally firing ammunition with which it is loaded will be lessened.

The invention consists in the combination, in a fire-arm, with the barrel, the stock and handle, the hammer, and the trigger, of a breech-piece having arms extending rearward upon opposite sides of the hammer to the stock and handle, pins or pivots and recesses or slots which said pins or pivots enter, whereby said breech-piece is adapted, when swung into a position in front of the hammer, to be carried forward by the hammer to fire the ammunition in the barrel.

In the accompanying drawings, Figure 1 is a side view of a toy pistol embodying my invention, and Fig. 2 is a top view of the same.

Similar letters of reference designate corresponding parts in all the figures.

The barrel A, stock and handle B, hammer C, trigger D, and lock mechanism of the pistols 30 may be of the ordinary or any suitable kind, except that there will be such a distance between the breech of the barrel and the hammer when forward that the latter cannot of itself come in contact with ammunition with 35 which the barrel is loaded, so as to fire the same.

E designates a breech-piece, which, on the side which is the nearer to the breech of the barrel A, is preferably provided with a rigidly-40 attached projection or firing-pin, a. It is supported by arms E', extending rearwardly from it and connected to the stock of the pistol.

The arms extend one on each side of the hammer and the stock of the pistol, and are secured to the latter by pins b, serving as pivots, 45 on which they may be swung upward and downward. These pins b are shown as extending from the stock of the pistol and fitting in recesses or openings in the arms E'; but they might extend from the arms and enter recesses 50 in the stock.

When the pistol is being loaded the breech-piece is swung upward into the position illustrated in dotted lines in Fig. 1, and then, the hammer being unable to reach the ammunition, 55 accidental firing thereof is obviated. As soon as it is desirable to fire the ammunition the breech-piece is swung downward into a position between the breech end of the barrel and the hammer, so that it can be impelled forward 60 by the hammer to effect the firing of the ammunition. This forward motion of the breech-piece E may be provided for by making the recesses or openings which the pins or pivots b enter in the form of elongated holes or slots, as 65 indicated by dotted lines in Fig. 1, so that the breech-piece and its arms may be impelled bodily forward by the hammer, as well as swung on the pins or pivots b.

What I claim as my invention, and desire 70 to secure by Letters Patent, is—

The combination of the barrel A, stock and handle B, hammer C, trigger D, breech-piece E, with its arms E' extending rearward upon opposite sides of the hammer to the stock and handle, and the pins or pivots b, and recesses or openings which they enter, the said breech-piece being adapted, when swung into a position 75 in front of the hammer, to be impelled forward by the hammer, substantially as specified. 80

EDWARD R. IVES.
